CLAIM

I claim the ornamental design for the dish drainer, as shown and described.

DESCRIPTION

FIG. 1 is a front view of a dish drainer according to the present application;

FIG. 2 is a rear view of a dish drainer according to the present application;

FIG. 3 is a left view of the dish drainer according to the present application;

FIG. 4 is a right view of the dish drainer according to the present application;

FIG. 5 is a top view of the dish drainer according to the present application;

FIG. 6 is a bottom view of the dish drainer according to the present application;

FIG. 7 is a first perspective view of the dish drainer according to the present application;

FIG. 8 is a perspective view of the dish drainer shown in an alternate position of use;

FIG. 9 is a bottom perspective view of FIG. 7; and,

FIG. 10 is an additional view of FIG. 7 with the cutlery holder shown in an alternate position for completeness of illustration.
